REFINING PROCESS

Amiot P. Hewlett, Summit, and Gerald E. Phillips, Cranford, N. J., assignors to Standard Oil Development Company, a corporation of Delaware

Application May 27, 1939, Serial No. 276,080

3 Claims. (Cl. 196—96)

The present invention relates to an improved process comprising a particular sequence of stages by which it is possible to produce high quality gasolines not heretofore secured by processes known in the art. The process of the present invention comprises cracking selected feed stocks under restricted vapor phase temperature and pressure conditions, passing the resulting vapors through bauxite and then through clay. If the feed oil comprises high sulfur stocks, respective fractions after bauxite and clay treat are segregated, acid treated and further refined in an optimum manner.

It is well known in the art to subject various petroleum oil feed stocks such as gasolines, gas oils, reduced crudes and the like to temperature and pressure conditions to form relatively lower boiling materials and relatively higher boiling materials. It is also known in the art to refine the resulting products by treatment with acid, clay, bauxite, and the like. The art of segregating the resulting product into various fractions in order to secure more efficient and economical refining operations is also known. The results secured seemed to be more or less additive and the assumption had been to a large extent that no interrelationship existed between the successive refining steps. For example, it had been assumed that one type of cracking operation could be readily substituted for another and that equivalent results would be secured in the subsequent refining of the petroleum stock.

However, we have now discovered that providing a certain sequence of carefully controlled stages be employed in the treatment of particular feed stocks, unexpected, desirable results are secured which could not be foreseen from disclosures in the art. We have discovered that if feed stocks are segregated into relatively high and into relatively low sulfur feed stocks and that if these feed stocks are then subjected to restricted vapor phase cracking conditions, an apparent chemical arrangement of the molecules occurs which seemingly renders the feed stocks susceptible to further rearrangement by subsequent treatment with bauxite, clay and acid in a manner to produce a high quality high octane number gasoline product. Apparently the vapor phase gasoline produced under the particular vapor phase cracking conditions employed is susceptible to isomerism and perhaps scission by subsequent treatment with bauxite and clay which results in a high quality gasoline.

The process of our invention may be readily understood by reference to the diagrammatical flow plan illustrating one modification of the same. For purposes of illustration, the vapor phase cracking system comprises two heating coils and a soaking drum or reaction chamber. Feed oil, which for the purposes of illustration

is assumed to be a high sulfur gas oil, is introduced into the lower part of primary tower 1 by means of fresh feed line 2. The fresh feed, together with cycle oil, is withdrawn from the bottom of primary tower 1 by means of line 3 and is introduced into heating coil 4, in which the temperature is raised the desired extent. In general, when operating as described, the oil is heated in coil 4 to a temperature somewhat below cracking temperatures. Under certain conditions it may be desirable to introduce a portion or the entire quantity of fresh feed directly into heating coil 4 by means of line 5. The heated oil is withdrawn from heating coil 4 by means of line 6 and introduced into drum 7. In drum 7 substantially the entire quantity of oil is vaporized and separated from a relatively small per cent of unvaporized material. The unvaporized material is removed from drum 7 by means of line 8 as a residue. This residue may be recycled, if desired, or may be discarded from the system. The vaporized oil is removed from drum 7 by means of line 9 and introduced into a secondary heating coil 10, in which the temperature is raised to cracking conditions. The heated oil is withdrawn from heating coil 10 by means of line 11 and introduced into soaking drum or reaction chamber 12, in which the oil is held under cracking conditions for a sufficient length of time to produce optimum conversion of the feed. A downflow soaking drum operation is illustrated, but it is to be understood that either a downflow or an upflow operation may be employed. The products are withdrawn from reaction drum 12 by means of line 13 and passed through a pressure release valve 14. The products under reduced pressure are released into evaporator or tar settler 15. Tar of the desired gravity, usually from 8° A. P. I. to 12° A. P. I., may be withdrawn from evaporator 15 by means of line 16. The vapors pass overhead from evaporator 15 through vapor line 17 into primary tower 1. Cycle stock accumulates in the bottom of primary tower 1 and vapors pass overhead through vapor line 18 into secondary tower 19. The temperature at the top of primary tower 1 is so adjusted as to secure the desired endpoint in the products withdrawn from the bottom of secondary tower 19. The temperature at the top of secondary tower 19 is controlled so as to produce an overhead distillate of the desired endpoint which is removed by means of line 20. This temperature is usually adjusted to produce an overhead product boiling below about 400° F. to 420° F. However, under certain operations the temperature may be somewhat higher and the desired endpoint product secured by a subsequent distillation operation. An intermediate boiling or heating oil fraction is withdrawn from the bottom of secondary tower 19 by means of

line 21. The vaporous overhead product from secondary tower 19 is preferably heated to the desired extent in heater 22 and then introduced by means of line 23 into bauxite treat 24. The oil is then withdrawn from bauxite treat 24 by means of line 25 and cooled in cooler 26. It is to be understood that cooler 26 may comprise a water cooler or a suitable heat exchanger, as for example, a feed oil to vapor heat exchanger. The cooled vapors are withdrawn from cooler 26 and introduced into clay treater 27. The bauxite and clay treated oil is then introduced into fractionating tower 28 by means of line 29. The temperatures and pressures maintained on tower 28 are adjusted to remove overhead by means of vapor line 30 hydrogen sulfide and gases boiling in the methane and ethane boiling range. The bottoms are withdrawn from tower 28 by means of line 31 and introduced into fractionating tower 32. The temperatures and pressures maintained on tower 32 are adjusted to remove overhead by means of vapor line 33 gases boiling in the propane and butane boiling range. These gases are preferably processed in a suitable polymerization plant and blended back with a finished gasoline in order to increase the yield of high octane number gasoline.

The bottoms from tower 32 are introduced into distillation unit 34 by means of line 35. A relatively lower boiling fraction is removed overhead by means of line 36, while a relatively higher boiling fraction is removed as bottoms by means of line 37. The relatively higher boiling fraction is acid treated in treating unit 38 with acid introduced by means of line 39. The acid sludge is removed from treating unit 38 by means of line 40. The acid treated oil is removed by means of line 41, soda washed in treating unit 42 and then introduced into distillation unit 43 by means of line 44. A residue is removed from distillation unit 43 by means of line 45, while the treated stable distillate is removed overhead by means of line 46 and combined with the lower boiling distillate removed overhead from distillation unit 34 by means of line 36.

It is to be understood that the operating procedure may be varied considerably within the scope of the present invention. For example, although it is preferred to employ two heating coils in series and to remove a residue prior to heating the oil to cracking conditions in the secondary coil, it is to be understood that under certain conditions a single heating coil may be employed. Under these conditions the oil would be heated to cracking temperatures in heating coil 4 and then introduced directly into reaction chamber 12 by means of line 47. Under certain conditions it may be desirable to employ a coil only operation, in which case the oil would be heated to cracking conditions in heating coil 4 and introduced directly into separator 15 by means of line 48. Valves 49, 50, 51, 52, and 14 could be readily adjusted to secure the desired operation. When operating in accordance with the preferred modification, the oil is preferably heated in heating coil 4 so that substantially complete vaporization will be secured in drum 7. The amount of residue withdrawn from drum 7 should be in the range from 1% to 5%. In general, it is preferred to bauxite treat only those gasoline fractions boiling in the gasoline range, as for example, those fractions having a boiling point below about 420° F. These fractions are removed overhead from the secondary tower and are preferably heated and then passed through

the bauxite. However, under certain conditions it may be desirable to condense the overhead vapors and to remove certain gases therefrom prior to passing the distillate through the bauxite. If this modification be employed, the overhead vapors from secondary tower 19 would be passed into cooler 53 by means of line 54 and then introduced into fractionating tower 55. Hydrogen sulfide and gases boiling in the methane and ethane range are preferably removed overhead from tower 55 by means of line 56. Bottoms are removed from tower 55 by means of line 57 and introduced into a subsequent fractionating tower 58. Temperature and pressure conditions are maintained on tower 58 in order to remove overhead by means of line 59 gases boiling in the propane and butane ranges. These gases are preferably processed in a suitable polymerization plant and blended back with a finished gasoline in order to increase the yield of desirable high octane number gasolines. Bottoms are removed from tower 58 by means of line 60 and passed through heater 22. This operation could readily be secured by adjusting valves 61, 62, and 63. In general, the oil is clay treated after being bauxite treated. It is to be understood, however, that under certain conditions, particularly if the oil has a satisfactory octane number, color and gum stability, it may bypass the clay treat by means of lines 64 and 66. If the feed oil comprises a low sulfur gas oil, as for example, a gas oil from East Texas crude, the product may be withdrawn by means of line 65. These operations may be secured by adjusting valves 67, 68, 69, 70, and 71. However, in general, it has been found that the preferred operation is to clay treat the bauxite treated oil, in which case low sulfur products would be withdrawn by means of line 72. It is to be understood that any suitable pumping means and the like may be employed, as well as any heat exchanging equipment, to secure a desired optimum operation.

When treating vapor phase distillates with sulfuric acid it has been found that the acid sludge separates with great difficulty and is extremely viscous and difficult to remove from the treating equipment. In addition to this, such acid treated distillates when passing through the customary water washing and neutralization stages form very stable emulsions with the result that considerable loss is encountered due to this emulsion formation. When bauxite and clay treating prior to acid treating, this difficulty is entirely avoided. The sludge produced separates very readily from the distillate and is extremely fluid in nature and is light in color. Furthermore, the acid treated distillate on being water washed and neutralized with caustic forms no emulsion and considerable saving is thus secured. The treating losses shown by the data presented do not take into account emulsion losses, but are merely losses which occur as sludge loss and polymer loss. In actual operation, however, when acid treating vapor phase cracked stock in the conventional manner, a considerably lower yield of product would be obtained due to emulsion losses which have not been taken into account.

The conditions of the present invention must be carefully controlled and a particular sequence of stages employed. The feed oils which are subjected to vapor phase cracking conditions may be any suitable petroleum oil. However, preferred oils are heavy naphthas and petroleum gas oils boiling in the range from about 400° F. to 900° F. These oils are preferably segregated into

relatively high and into relatively low boiling oils. Relatively low boiling oils are those oils having at least 90% distilled at 700° F., Engler, while relatively high boiling oils are those oils having about 90% distilled at 900° F. The feed oils are also segregated into relatively high and into relatively low sulfur stocks. Relatively low sulfur feed stocks are feed oils from which vapor phase cracked distillates containing less than about 0.3% sulfur are produced, while relatively high sulfur feed stocks are feed oils from which vapor phase cracked distillates containing from about 0.3% to 1.0% are produced.

The particular vapor phase cracking conditions employed will be varied somewhat with respect to the character of the petroleum oil being processed. However, in general, the oils are subjected in the vapor phase to pressures in the range from about atmospheric to 250 pounds gage pressure, preferably to pressures less than about 200 pounds gage. The oil cracking temperatures employed are in the range from about 970° F. to 1400° F., preferably in the range from about 1000° F. to 1200° F. If the feed oil is a relatively low boiling oil, desirable vapor phase cracking results are secured by cracking at an oil temperature in the range from about 970° F. to 1000° F. and at a pressure in the range from about 150 pounds to 200 pounds gage. However, if the feed oil comprises a relatively high boiling oil, preferred oil temperatures are in the range above about 1150° F. and preferred pressures in the range below about 60 pounds gage.

The products removed from the cracking coil are passed in the vaporous state through a bed of bauxite at a temperature in the range from about 600° F. to 850° F. It has been found that temperatures in the range from about 800° F. to 850° F. are especially desirable. Under certain conditions it may be desirable to entirely condense the distillate and to separate the uncondensed gases therefrom. The separated gases may be burned, but are preferably treated in a polymerization plant to further increase the yields of high quality, high octane number gasoline. Feed rates through the bauxite will vary and, to a large extent, will depend upon the particular petroleum oil being treated. However, in general, we have found that a feed rate of one liquid volume per volume of catalyst per hour will give desirable results. The bauxite treated material is then cooled and passed through clay at a temperature in the range from about 340° F. to 600° F., preferably at a temperature of 400° F. to 500° F. Attapulgus clay is preferably used, although other clays such as acid treated clays are also satisfactory. Gases may be separated from the bauxite and clay treated distillate by passing the treated distillate into a separation drum. The separated gases may be burned, but are preferably passed through a suitable polymerization plant to further increase the yield of high quality gasoline.

When processing relatively high sulfur stocks the amount of bauxite and clay treated light fraction removed overhead in the distillation step, thus bypassing acid treat, may vary considerably. However, the amount removed overhead should be about 60% to 80% of the bauxite and clay treated material, preferably about 70%. The undistilled bottoms are acid treated with an optimum amount of acid which will depend upon the properties of the oil being treated. In general, it has been found that desirable results are secured by treating the oil with from about 20

75 pounds to 25 pounds of 98% acid per barrel of oil or its equivalent. The acid treated oil after removal of the acid sludge is then washed with sufficient soda in order to neutralize the acidic constituents remaining in the oil. The acid soda treated oil is then rerun under conditions in which about 95% to 98% is removed overhead and blended with the bypassed distillate.

In order to further illustrate the present invention, the following examples are given which should not be construed as limiting the invention in any manner whatsoever:

EXAMPLE 1

15

A light petroleum fraction boiling in the gasoline range and produced from a high sulfur gas oil by cracking said gas oil in the vapor phase at a temperature of about 1050° F. and a pressure of about 60 pounds per square inch gage was treated in the vapor phase with bauxite at a temperature of about 800° F. and was then passed through clay at a temperature of about 450° F. An analysis was made of the oil before and after 20 bauxite and clay treatment. The results of the 25 analysis were as follows:

TABLE 1

30

	Before bauxite and clay treatment		After bauxite and clay treatment	
	Per cent	Per cent	Per cent	Per cent
35 Aromatics	6		5	
Straight chain olefins	37		42	
Branched olefins	4		10	
Unsaturated naphthenes	41		30	
Saturated naphthenes	6		[6]	
40 Straight chain paraffins	5.5	12	[5]	13
Branched chain paraffins	0.5		[2]	

45

The above data indicate that isomerism and some scission seem to be essential reactions taking place and are apparently the explanation for the high octane number improvement which results from bauxite and clay treatment of these particular stocks. It should be noted that no substantial change occurred with respect to the amount of saturated naphthenes and saturated 50 paraffins present.

EXAMPLE 2

55

Gas oils from East Texas crudes were cracked under various conditions to secure petroleum fractions boiling within the gasoline range. The cracked naphthas from the respective processes were then subjected to a bauxite and clay treatment. The results of these operations were as follows:

60

¹ A. S. T. M. octane number determination: Described in the Committee D-2 Report of A. S. T. M. Standards on Petroleum Products and Lubricants, A. S. T. M. designation D-357-38T.

² Volume of tetraethyl lead as given in tables is cubic centimeters per gallon.

The above data clearly illustrate the fact that the bauxite and clay treat is far more effective in the treatment of the vapor phase cracked stock than in the treatment of oils cracked in the liquid phase.

EXAMPLE 3

A high sulfur gas oil was cracked at a high pressure and a similar sample was cracked in the vapor phase at a temperature of about 1050° F. and at about 60 pounds pressure. Portions of the respective stocks were acid treated, while other portions were treated with bauxite, clay and then acid. The results of these finishing operations may be summarized as follows:

TABLE 3

Finishing high sulfur cracked distillates produced by vapor phase cracking and by high pressure cracking respectively, by combination with bauxite, clay and acid treating

	Distillate produced at about 1050° F. and a pressure of less than 60 lbs./sq. in.		
	Per cent sulfur	# 98% acid/barrel	Total treating loss (volume per cent)
Untreated gasoline.....	0.338	None	None
Acid treated.....	0.104	11.4	14.8
Bauxite, clay and acid.....	0.096	7.2	4.6
High pressure distillate			
Untreated gasoline.....	0.273	None	None
Acid treated.....	0.101	7.44	4.3
Bauxite, clay and acid.....	0.099	3.78	2.8

From the above data it may be seen that the sludge loss was considerably decreased when treating the vapor phase gasoline with bauxite, clay, and acid, over the use of acid alone. It may

also be seen that the sludge loss was not materially decreased when treating the high pressure distillate with bauxite, clay, and acid, over acid treatment alone.

5

EXAMPLE 4

A large crude having a gravity of 16° to 17° A. P. I. and a sulfur determination of 2.35 was distilled in a manner to remove about 7% naphtha and to recover about 37% gas oil having a gravity of about 26° A. P. I. The inspection of the gas oil was as follows:

60 Gravity °A. P. I.....	Per cent distilled at 356° F.....	85.0
60 Gravity °A. P. I.....	Final boiling point.....	407

The above blended gasoline was then handled by three different processes as follows:

Process 1

The petroleum fraction was distilled taking overhead 24% light ends. The bottoms were treated with 15 pounds of 98% acid per barrel of oil. The treating loss amounted to 19.4%, based upon the oil being acid treated. The acid treated product was then soda washed and rerun, taking overhead 88%. The overhead product was blended with the original light distillate and the total sweetened.

Process 2

The petroleum fraction was distilled and 60% light ends removed overhead. The bottoms were then treated with 35 pounds of 98% sulfuric acid. The treating loss was 26%, based upon the oil being treated. The acid treated bottoms were then soda washed and rerun, taking 88% overhead. The overhead was blended with the original bypassed distillate and passed through clay at a temperature of 450° F. and then sweetened.

Process 3

The entire petroleum fraction was passed through bauxite at a temperature of about 800° F. and then passed through clay at 410° F. at atmospheric pressure. The bauxite and clay treated distillate was washed with sodium carbonate. The washed distillate was distilled and 75% light ends removed overhead. The bottoms were treated with 25 pounds of 98% acid per barrel of oil. The treating loss amounted to 10%, based upon the oil being acid treated. The acid treated bottoms were soda washed, rerun and blended with the original bypassed distillate.

The acid requirements, based upon the total volume of gasoline being processed, were as follows:

TABLE 8

Acid required, 98% H ₂ SO ₄		
Process 1	lbs. per barrel	11.4
Process 2	do	14.0
Process 3	do	7.2

The inspections of the gasoline produced by the respective processes were as follows:

TABLE 9

	Proc- ess 1	Proc- ess 2	Proc- ess 3
Yield volume per cent.	83.6	87.3	94.4
Gravity °A. P. I.	55.4	55.8	54.1
Sulfur determination per cent.	0.104	0.104	0.098
Color (Saybolt)	26	26	28
Colorhold—16 hrs. at 212° F.	23	23	26
Breakdown minutes	15	10	15
+0.4 lb. U. O. P. #4 inhibitor per 1000 gals.	260	285	355
Copper dish gum mg.	59	115	61
+0.4 lb. U. O. P. #4 inhibitor per 1000 gals.	14	9	12
Octane No. clear (A. S. T. M.)	75.7	77.5	78.1
+1½ cc. tetraethyl lead (A. S. T. M.)		81.3	
+3cc. tetraethyl lead (A. S. T. M.)	81.5	82.4	82.7

From the above data it is to be observed that a considerably higher yield was secured by Process 3 with an appreciable saving in acid. It is also to be observed that the octane number of the gasoline produced by Process 3 was considerably higher than the octane number of the gasoline produced by Process 1 or Process 2.

EXAMPLE 5

A low sulfur East Texas gas oil having a gravity of 33.3° A. P. I. was cracked in a once-through coil operation at a temperature of 1025° F. and at a pressure of about 60 pounds per square inch gage. The naphtha distillate was then passed through bauxite at a temperature of about 800° F. and then through clay at a temperature of about 500° F. Inspections were determined on the naphtha distillate before and after passing through the bauxite and clay with the following results:

TABLE 10

	Naphtha inspection	Total distillate	800° F. 500° F. bauxite and clay

¹ 18 Robinson.

² +28 Saybolt.

From the above data it is to be observed that the octane number was considerably improved by passing through bauxite and clay and that very little, if any, polymerization resulted.

EXAMPLE 6

A low sulfur East Texas gas oil was cracked at a pressure of 740 pounds per square inch and at a temperature of 940° F. The naphtha distillate was passed through bauxite at a temperature of about 800° F. and through clay at a temperature of about 400° F. The inspections of the naphtha before and after treatment were as follows:

TABLE 11

+5 mg. U. O. P. #4 inhibitor per 1,000 gals.		220
Copper dish gum mg.	16	18
+5 mg. U. O. P. #4 inhibitor per 1,000 gals.		5
Octane No. clear (A. S. T. M.)	68	70
+1½ cc. tetraethyl lead (A. S. T. M.)	74	77
+3cc. tetraethyl lead (A. S. T. M.)	77	78

From the above data it may be seen that the octane number was not materially altered by the bauxite and clay treat.

EXAMPLE 7

A high sulfur West Texas gas oil was cracked at a temperature of 925° F. and at a pressure of about 750 pounds per square inch. The cracked distillate was handled by various means with the following results:

TABLE 12

	Process 1 stabilized and rerun to 400° F. end point	Process 2 bauxite 800° F. 100% pres.	Process 3 "2"+ clay 450° F.
Yield volume..... per cent.	87	84	84
Gravity °A. P. I.....	57.1	56.2	56.7
Sulfur determination..... per cent.	0.250	0.137	0.139
Color.....	+16	+15	+29
16 hrs at 212° F.....	+14	+15	+24
Aniline point.....	108	106	109
Acid treat.....	39	31	35
Breakdown.....	95	25	35
+5 mg. U. O. P. #4 inhibitor per 1,000 gals.....	305	420	605
Copper dish gum.....	17	25	24
+5 mg. U. O. P. #4 inhibitor per 1,000 gals.....	6	8	7
Octane No. clear (A. S. T. M.).....	66.0	67.1	68.4
13cc. tetraethyl lead.....	72.1	73.5	74.9
3cc tetraethyl lead.....	75.0	77.2	78.1
Initial boiling point, Engler.....	95	93	94
Percent distilled at 212° F., Engler.....	27.5	25	26.5
Percent distilled at 257° F., Engler.....	42.5	40	41
Percent distilled at 374° F., Engler.....	88.5	86	86.5
Final boiling point, Engler..... °F.	410	412	408

It is apparent from the above data that the bauxite and clay treat have little effect on a petroleum oil cracked in the liquid phase.

EXAMPLE 8

A gas oil was cracked in the vapor phase at a pressure of about 60 pounds gage and at a temperature of 1060° F. The cracked distillate was passed through bauxite at a temperature of about 800° F. and through clay at a temperature of about 500° F. Atmospheric pressure was employed on the bauxite and clay treat. Feed rates through the bauxite and clay treat were one liquid volume per volume of bauxite and per volume of clay per hour.

The octane number improvements secured by the bauxite and clay treat were as follows:

TABLE 13

Octane number improvements (A. S. T. M.) secured by

	Bauxite	Clay	Bauxite+ clay
Operation 1.....	5.2	0.5	5.7
Operation 2.....	4.5	0.7	5.2

The above data demonstrate that the clay

treat further improves the octane number characteristics of the fuel.

The process of the present invention is not to be limited by any theory or mode of operation, but only by the following claims in which it is desired to claim all novelty in so far as the prior art permits.

We claim:

1. Process for the production of high quality, high octane number motor fuels comprising cracking a petroleum oil in the vapor phase at a pressure in the range below about 60 pounds gage and at a temperature in the range from about 1100° F. to 1400° F., passing cracked petroleum fractions boiling in the gasoline range through bauxite at a temperature in the range from about 800° F. to 850° F., then passing said bauxite treated oil through clay at a temperature in the range from about 340° F. to 500° F., cooling said petroleum oil to secure said high quality motor fuels.

2. Process for the production of high quality, high octane number fuels comprising cracking a petroleum oil, boiling in the gas oil range and having about 90% distilled at 900° F., in the vapor phase at a pressure in the range below about 60 pounds gage and at a temperature in the range from about 1100° F. to 1400° F., passing cracked petroleum fractions boiling in the gasoline range through bauxite at a temperature in the range from about 800° F. to 850° F., then passing said bauxite treated oil through clay at a temperature in the range from about 340° F. to 500° F., cooling said petroleum oil to secure said high quality motor fuels.

3. Process for the production of high quality motor fuels from petroleum oils comprising cracking a petroleum oil in the vapor phase at a pressure in the range from about 0 pounds to 200 pounds gage and at a temperature in the range from about 975° F. to 1400° F. under conditions in which a cracked fraction boiling below about 400° F. is segregated and removed overhead in a fractionating tower, heating said segregated cracked fraction to a temperature in the range from about 800° F. to 850° F. and passing the same through bauxite in order to produce said high quality motor fuel.
